KENNETH L. PORTER, OF NEW ROCHELLE, NEW YORK

RADIATOR INCLOSURE

Application filed November 1, 1928. Serial No. 316,492.

This invention relates generally to radiator inclosures and more particularly to radiator inclosures constructed of separable parts which can be variously manipulated to accommodate the inclosure to a variety of radiators.

Since radiators occur in such a variety of types and sizes, and each is furthermore equipped with a variety of piping connections to conform with existing circumstances and conditions, it has generally been considered impractical to construct radiator inclosures in such vast variety and keep them in stock. This is especially true of radiator inclosures of the type which completely house the radiator. It has therefore been the custom of manufacturers and dealers to supply radiator inclosures on a made to order basis only, each inclosure being specially 10 and rigidly constructed to fit the particular radiator to which the same is to be applied.

Made to order radiator inclosures present a number of objectionable features. Since each inclosure is made specially for a particular location, the first cost thereof is necessarily high. Their rigidity and non-flexibility make them inconvenient and costly to install. For example, mistakes in measurements and miscalculation of location conditions often make it necessary to rebuild the inclosure or supply another properly constructed for the particular location.

Furthermore, it is sometimes desirable to remove the radiator inclosure from one radiator and place it over another. For example, radiator inclosures are often installed by the tenant or occupant. In such cases the inclosures constitute personal property, subject to removal from the building with the home furnishings. It is unlikely however, that a rigidly constructed inclosure, built for one location, will properly fit in another. In any event, a rigid inclosure is difficult to remove and replace and this cannot be done without loss of time, much expense and frequent damage. Consequently such radiator inclosures constituting the personal property of the tenant or occupant are often left with the realty when the premises are vacated.

A principal object of my invention is to

provide a radiator inclosure constructed of separable parts, which parts can be carried in stock by supply houses and are adapted to be readily manipulated to accommodate the inclosure to different radiators and location 55 conditions.

Another object of my invention is to provide an adjustable radiator inclosure which can be easily and quickly removed from one radiator and replaced upon another, that is 60 strong and durable, ornamental in appearance and pleasing to the eye, that it low in first cost and economical to install and further flexibly adapted to various needs.

Other objects of this invention will be 65 pointed out hereafter or become obvious as the disclosure proceeds.

In order that a clearer understanding of my invention may be had, attention is hereby directed to the accompanying drawings, 70 forming a part of this application and illustrating certain possible embodiments of this invention.

Referring to the drawings Fig. 1 is a perspective view of my radiator inclosure constructed of telescoping sections;

Fig. 2 is an exploded front face view of the radiator inclosure shown in Fig. 1 the parts being separated to more clearly disclose the particular construction of the parts;

Fig. 3 is a transverse vertical cross sectional view, taken on line 3—3 of Fig. 1;

Fig. 4 is a horizontal cross sectional view taken on line 4—4 of Fig. 1;

Fig. 5 is an enlarged fragmentary cross sectional view of a portion of my inclosure taken on line 5—5 of Fig. 1 particularly showing the means for adjusting the length of the inclosure leg supports;

Fig. 6 is a perspective view of my separate leg element adapted to be applied at any location along the front wall of the inclosure;

Fig. 7 is an enlarged fragmentary cross sectional view of a portion of my inclosure taken on line 7—7 of Fig. 1 showing particularly one means of securing my telescoping sections together;

Fig. 8 is a horizontal cross sectional view of a modified form of radiator enclosure similar to that shown in Fig. 1 except that the

side and end walls of the telescoping sections are formed from a single piece of sheet material;

Fig. 9 is a perspective view of a sectional 5 radiator inclosure of modified construction;

Fig. 10 is an enlarged perspective view of the rear section of the radiator inclosure shown in Fig. 9, this section comprising two telescoping parts, each part having a top wall 10 portion and a rear wall portion;

Fig. 11 is an enlarged perspective view of the front section of the radiator inclosure shown in Fig. 9, this section comprising two telescoping parts, each part having an end 15 wall portion and a front wall portion;

Fig. 12 is a transverse vertical cross sectional view of my modified radiator inclosure taken on line 12—12 of Fig. 9;

Fig. 13 is an enlarged fragmentary detail 20 taken on line 13—13 of Fig. 10 showing particularly one method of securing the front and rear sections of my modified inclosure construction together;

Fig. 14 is an enlarged fragmentary detail 25 taken on line 14—14 of Fig. 9 showing one method securing the front wall portion to the top wall portion of my inclosure.

Similar reference characters refer to similar parts throughout the several views.

Referring to Figs. 1 to 7 inclusive, of the drawings, my radiator inclosure here shown comprises two sections of substantially similar shape. The left hand section shown in the exploded view Fig. 2 of the drawings 30 comprises generally a front wall portion 1, an end wall portion 2, and a rear wall portion 3 secured together at the corners by angle iron leg members 4. The top wall or table portion 5 may be made integrally continuous 35 with the front and rear wall portions as shown more clearly in Fig. 3. The top wall portion is preferably provided with a front ledge portion 6, a rear ledge portion 7 and an end ledge portion 8, simulating in all 40 respects a table top.

The right hand section of my inclosure is substantially similar to the left hand section comprising generally a front wall portion 9, top wall portion 10, rear wall portion 11, and 45 the respective front, rear and end ledge portions 12, 13 and 14 respectively, all bent out from a single piece of sheet material. An end wall 15 is also provided which is secured to the front and rear wall portions by means 50 of angle iron leg member 16 as shown in Figs. 1 and 4.

The left hand section is of such size as to telescope snugly into the right hand section, as shown in Fig. 3. In order to 55 conceal the joint caused by the overlapping sections, and also, if necessary, to support the inclosure at its midsection, the telescoping end of the right hand section is provided with a leg formation as shown in Figs. 1, 2 and 4. This leg formation consists of a strip

of sheet material bent to the general contour of the inclosure, having a leg portion 17, a foot portion 18 and a top strip portion 19, the whole preferably permanently secured to the inclosure section. The lower leg portion 70 may be stamped and bent to simulate a square, round or other shaped leg, well known to the stamping art.

In order to architecturally balance the whole when assembled and also to provide, if necessary, an additional mid-section support, another leg formation is secured to the inclosure after the sections have been telescopingly assembled. This leg formation is shown in perspective view in Fig. 6 and 75 comprises generally a bent strip having a leg portion 20, foot portion 21 and top strap portion 22 all bent to conform to the general contour of the inclosure. Now the front wall of the left hand section has a leg portion 23 stamped out of the sheet, as shown more clearly in Figs. 2 and 3. The end of this leg portion may be turned inwardly and upwardly to form in effect, a foot 24, as shown in Fig. 3. The rear wall of the left hand inclosure section is similarly stamped to form a rear leg portion 25 the end of which is also turned inwardly and upwardly to form foot 26. This leg may be of such length as to rest directly on the floor. Similarly the rear wall of the right hand section is stamped to form a rear leg portion 26' of such length as to rest directly on the floor.

The left and right hand sections are telescoped together so as to form an inclosure 100 of the proper length, and the leg formation strip 20 is then applied. The foot 21 of the leg formation strip is placed under the foot 24 of the leg portion 23 as shown in Fig. 3. The strap portion 22 is swung over the table 105 portion of the inclosure and may be provided with a rolled end 25 which springs into engagement with the corner of the rear ledge portion 13 holding the strip in place. It is evident however, that other means of securing the strip to the inclosure may be used within the purview of this invention. Leg formation 20, secured as above to the inclosure, is spaced the same distance from the right hand end of the inclosure as leg formation 17 is spaced from the left hand end of the inclosure. The inclosure is thus divided into panels which are architecturally and artistically balanced to give a pleasing effect to the whole.

To secure the sections together, I drill holes 26" through the front wall of both sections and insert bolt members therein. These bolt members have a reduced body portion 27 and a topped over lug portion 28. The hole 26" 125 is larger than the body of the bolt as clearly shown in Fig. 7 so that the bolt body can be readily inserted therein. The lug portion drops down and engages with the periphery of the hole, firmly securing the sections to- 130

gether. To improve the appearance of the front wall panel, the bolt members may be provided with decorative or rosette heads 29, as shown in Fig. 1. The sections are also secured together at the back. The rear portion of the left hand section has a hole drilled therein and a nut member 30 welded around the hole on the inside face of the rear panel, as shown in Figs. 2 and 3. The rear portion 10 of the right hand section is provided with a plurality of correspondingly placed longitudinally extending slots 31. A bolt member 32 having a winged head is adapted to be inserted through the slot and hole of the respective sections and turned into engagement with the nut member 30. By manipulating the bolt member the rear portions of the sections can be securely clamped together.

20 Since the floor surface surrounding the radiator is not always level and even, I preferably supply each leg member and particularly the corner legs 4 and 16 with some adjustable elevating means. I accordingly 25 weld a nut member 33 to each leg at the lower end thereof, as shown more clearly in Fig. 5. A screw bolt 34 having a large round head 35 is provided, which turns into the nut member 33. As is evident, by turning the bolt 20 to the right or left, the leg support is correspondingly extended or contracted in length, so as to accommodate the unevenness of the floor. The bolt may be provided with a grip portion 36 to facilitate turning thereof.

It is sometimes desirable to not only cover the radiator but also cover the radiator control valve and pipe connections. The inclosure can be longitudinally extended to accomplish this. A flap door 37 may be provided in the end wall through which the control valve and air valve of the radiator may be reached to regulate and control the same. Such a flap door may be provided in 45 both ends of the inclosure to accommodate radiators with either right hand or left hand valves.

In Fig. 8 I have shown a slightly modified construction in which the front, rear, top 50 and end portions of each section is stamped or bent from a single and continuous piece of sheet material. Thus the sheet forming the front wall 38 of the left hand section may be bent at a right angle to form the end wall 39, again at a right angle to form the rear wall 40, and the rear wall may carry a sheet portion which may be stamped to form the top or table portion of the radiator, similar in cross sectional contour to that shown in 55 Fig. 3, the top portion being suitably secured to the top edge of the front portion 38 to form a rigid, unitary section. The right hand section of the radiator inclosure shown in Fig. 8 may be similarly formed, the sheet of 60 material forming the front wall portion 40

being bent at a right angle to form the end portion 42; again at a right angle to form the rear portion 43 and the top portion, integral with the rear portion, properly bent and stamped to shape and secured to the top edge 70 of the front portion of the section, forming a unitary whole. Leg adjusting nuts 36 may be secured in the corner of each section, and leg formation strips 17 and 20 secured to the section as before.

I have also devised a modified separable inclosure construction, shown more particularly in Figs. 9 to 14. This modification is made generally of two sections, the rear section being shown in Fig. 10 and the front section in Fig. 11. The rear section comprises two parts, one telescoping within the other. The right hand part of the rear section shown in Fig. 10 comprises a rear wall portion 44, the top of which is bent at a right angle to form a top or table portion 45. The top portion has a downturned front edge 46, as clearly shown in Fig. 12.

The left hand part of the section is similar in general to the right hand part, but is of such a size as to permit the right hand section to telescope snugly therein. The left hand part generally comprises a rear portion 47 and a top or table portion 48. The lower edge of the rear portion is inturned and upturned to form a channel 49, in which the lower edge of the right hand rear portion is adapted to slide. The front edge of the top portion is also bent into a channel formation 50, in which flange 46 of the right hand portion may slide. Thus it is seen that a rear section comprising two telescoping parts is presented.

The front section also comprises two telescoping parts, the right-hand part telescoping into the left-hand part, as clearly shown in Fig. 11. The right-hand part comprises generally a single sheet of material bent to form a front wall portion 51 and an end wall portion 52. An angle-iron leg member 53 may be used to brace the corner. A rear leg member 54 may also be provided, consisting of a single flat strip secured to the rear edge of the end wall. The lower end of the strip may be bent inwardly to form a foot 55.

The left-hand part of the front section is substantially similar to the right-hand part, consisting generally of a single sheet of material bent to form a front wall portion 56 and an end wall portion 57. An angle-iron leg 58 braces the corner, and a leg strip 59 supports the rear edge of the end wall. The lower edge of the front wall portion 56 is bent into channel form 60 into which the lower edge of the right-hand front wall portion 51 may slide. The upper edge of the front wall portion is similarly bent into channel form 62 and receives the upper edge of the right-hand front wall portion. It is now seen 130

that the right and left hand parts of the front wall section can be telescopingly extended or collapsed to form an inclosure of the desired length. The rear section is also 5 telescoped accordingly.

To provide a midsection support, the free edge of the front wall is bent back and doubled over to simulate a leg formation 63. It is understood that the front wall is so cut 10 and stamped as to provide for the additional metal required to make that leg portion extending below the sheet and also the foot portion 64. It is believed that the requirements of this stamping operation will be evident to 15 those skilled in the art from a study of Fig. 11, and therefore need not be described in detail. When the left and right hand parts of the front section have been properly adjusted to present an inclosure of the proper 20 length, the two sections can be secured together by bolts 27 (shown in Fig. 7) in the manner heretofore described.

To divide the front wall into architecturally balanced panels, a front leg formation 65 may be secured to the front wall. This leg formation consists of a heavy strip, the lower end of which is bent inwardly to form a foot portion 66 and then bent upwardly to form a brace portion 67, as clearly 25 shown in Fig. 12. The right-hand front wall panel 51 and brace portion 67 may then be welded or otherwise secured together as at 68. The top portion of the leg strip is bent inwardly and downwardly to form a 30 channel 69. The right-hand front wall panel 51 and the channel leg may be welded or otherwise secured together at 70, as above. The telescoping of the panel will thus not be interfered with.

40 Means are provided for detachably securing the front and rear sections together. A lug member 71 of angle iron form is secured along the outer edge of each of the rear wall portions, as shown in Fig. 10. A cooperating 45 slot member 72, also of angle iron form, is secured to each end wall, as shown in Fig. 11. It is clear that by manipulating the rear section the lug members 71 can be dropped into 50 engagement with the slot members 72 secured to the front section, thus locking the sections together. To more securely hold the sections together, channel members 73, as shown in Figs. 10 and 14, may be welded or otherwise secured at the outer ends and along the 55 front edge of each top wall portion. These channel members are adapted to engage the top edge of the end walls and front walls respectively when the rear section is dropped into operative engagement with the front 60 section.

In order to accommodate the radiator valve when disposed outside of the inclosure, an arched opening 74 may be cut into the lower portion of each end wall. A flap door 75, 65 permitting access to the radiator valve, and

an additional flap door 76, permitting access to the air valve of the radiator, may be provided in each end wall. The lower ends of the angle-iron corner legs 53 and 58 may be variously formed and stamped into rounded 70 or polygonal form. Leg adjusting bolts 34 may be provided on the corner legs as before, to adjust the length thereof as the surrounding floor surface may require.

It is understood that within the purview 75 of this invention, the sections shown in Figs. 10 and 11 may be interchanged, that is, the front section may comprise the telescoping front panel portions and top wall portions, and the rear section may comprise the end 80 walls and telescoping rear panel portions. Considering then Fig. 10 as the front section, the front face of the walls 44 and 47 would be suitably decorated and paneled as shown in Fig. 11 with the angle iron corner legs and 85 intermediate leg formations incorporated therewith.

In this modification, the entire radiator 90 inclosure is assembled to reach the user in two separate sections, the rear section shown in Fig. 10 and the front section shown in Fig. 11. The front section may first be telescoped to the proper length and then placed over the radiator. The rear section, similarly 95 telescoped, may then be dropped into position, lug members 71 dropping into engagement with the slot members 72, and the channel members 73 telescoping over the respective top edges of the front section, securing the sections together in a unitary 100 whole. The bolt members 27 can then be inserted, to rigidly secure the inclosure assembly together.

My separable inclosure construction may be made of any sheet material that will withstand abuse or wear, such as pressed fiber 105 material, bakelite or sheet metal. The front wall panels are perforated to permit the heat from the radiator to escape into the room. The rear and end walls of the inclosure are 110 preferably solid so as to direct the heat forwardly through the front panel perforations into the room. The front and end panels, the top table portion, leg members and post formations may all be variously decorated and 115 designed to give a pleasing effect to the whole.

It is now seen that I have provided a 120 radiator inclosure constructed of sectional units, which units are adapted to be carried in stock by the various supply houses. Since all possible variations in radiator lengths have been taken care of by my sectional construction, only a very few sizes, different as to width and height, need be made. This is not 125 objectionable and my radiator inclosure can thus be made cheaply and in quantities, and kept in stock readily available to the user. My inclosure can moreover be applied to the radiator by the ordinary workman or householder.

As many changes could be made in the above construction and as many apparently widely different embodiments of this invention could be made without departing from the scope thereof, it is intended that all 5 matter contained in the above description or shown in the accompanying drawings shall be interpreted as illustrative and not in a limiting sense.

What I claim is:

10 1. A radiator inclosure of the character described, including in combination, a plurality of sections adapted to telescope one within the other, a leg formation at the telescoping end of one of said sections, and means 15 for securing said sections together.

20 2. A radiator inclosure of the character described, including in combination, a plurality of telescopic sections each having a front wall portion, a leg element adapted to be secured to said telescoped sections in any location along the front wall thereof, and means for 25 securing said sections together.

30 3. A radiator inclosure of the character described, including in combination, two separable sections each adapted to enclose one end and a side wall portion of the radiator, leg formations at both ends of each of said sections, and means for securing said sections together.

35 4. A radiator inclosure of the character described, including in combination, two separable sections, each section having a top wall portion and front, rear and end side wall portions, said sections being movable longitudinally toward and away from each other to accommodate the enclosure to radiators of different lengths, a leg element adapted to be secured to said sections in any 40 location along the front wall thereof, and means for securing said sections together.

45 5. A radiator inclosure of the character described, including in combination, a plurality of telescopically adjustable sections, each of said sections having a top wall portion, a side wall portion and leg formations at both ends thereof, and means for securing said sections together.

50 6. A radiator inclosure of the character described, including in combination, a pair of telescopic sections, one overlapping the other, and each having a front wall portion, a panel strap formation having a supporting leg portion at the telescoping end of the overlapping section, and means for securing said sections together.

55 7. A radiator inclosure of the character described, including, in combination, an enclosing wall and a separate panel strap support for the inclosure adapted to be secured across said wall in any location thereon.

60 8. A radiator inclosure of the character described, including, in combination, an enclosing wall and a separate panel strap support 65 for the inclosure adapted to be secured across

said wall in any location thereon, said panel strap support having a supporting leg portion projecting below said wall.

9. A radiator inclosure of the character described, including a pair of adjustably telescoping sections, one overlapping the other, and each having a front wall portion, a panel strap formation having a supporting leg portion at the telescoping end of the overlapping section, and a separate panel strap having 70 a supporting leg portion adapted to be secured across the front wall portion of either one of said sections in any location thereon, whereby the front of the inclosure may be given a symmetrical appearance, said leg 75 portions supporting the inclosure at different points.

10. A radiator inclosure of the character described, including, in combination, an enclosing wall comprising two sections relatively adjustable laterally to vary the length of the inclosure, and a separate panel support for the inclosure adapted to be secured across the face of said wall in any location 80 thereon.

11. A radiator inclosure of the character described, including, in combination, an enclosing wall comprising two sections relatively adjustable laterally to vary the length of the inclosure, and a separate panel support 85 for the inclosure adapted to be secured across the face of said wall in any location thereon, said separate panel support having a supporting foot portion extending below said 90 wall.

This specification signed this 31st day of October, 1928.
